UNITED STATES PATENT OFFICE

GEORGE EDWARD PRUESSNER, OF CHESTERFIELD, MISSOURI

AMUSEMENT APPARATUS

Application filed April 18, 1932. Serial No. 605,835.

This invention relates to amusement apparatus, the subject matter of which is divided out of an original application for Letters Patent of the United States, Serial No. 566,185, filed October 1, 1931. The general object of the invention is to produce a recreational apparatus for users of all ages, but children in particular, by which the user derives not only mere amusement, but receives the benefit of exhilarating physical and gymnastic exercise, the present invention having more particularly to do with the novel cooperative arrangement of a swing and a taking off platform device or the like in the combination or combinations and arrangement or arrangements as hereinafter more fully described and pointed out with particularity in the appended claims.

In the accompanying drawing, forming a part of this specification, and illustrating a practical adaptation of the invention,—

Fig. 1 is a view illustrating a swing in cooperative relation to a taking off device in accordance with the invention, the supporting frame for the swing being shown in vertical longitudinal section and the swing itself and the taking off device being shown in side elevation; and

Fig. 2 is a perspective view of the taking off device alone.

Referring now to the drawing, the numeral 5 designates generally a supporting frame for the swing, said frame comprising a horizontal top cross member 6 supported at its end 35 on the substantially A-shaped side frame comprising the inclined leg members 7 and cross brace member 8, it being, of course, understood that a similar side frame supports the opposite end of the top cross member 6. So, 40 too, it is obvious that the leg members 7 may be braced with respect to the top cross member 6 by diagonal braces, not shown. The particular construction of this supporting frame for the swing does not in itself constitute any part of the present invention, it 45 being understood that the swing may be suspended from any other suitable support provided on the ceiling of a room or from the limb of a tree or other supporting arm.

The particular swing illustrated, and designated generally by the numeral 9, is of a single suspension type. That is to say, it 50 comprises a single suspension member, preferably a rope, flexible wire cable, or chain, attached at its upper end to the supporting

frame top cross member 6 or other suitable support, by swivel or universal coupling 10. As shown, said coupling 10 comprises an eye member 11 firmly secured to the end of the swing rope, cable, or chain 9, and interengaging with universal movement in eye 12 at the lower end of a bolt 13 passed upwardly through the top cross member 6 of the supporting frame and secured in place by cooperating jam nuts 14 on the upper end portion of the bolt. At the lower end of the swing member 9 is centrally attached a circular disc-like seat member 15, and for a considerable distance upwardly from the seat member 15 the swing suspension member 9 is covered by a tubular member 16 of rubber or other suitable flexible, and preferably elastic, material to provide a padded hand hold in convenient location to be grasped by the user and to prevent injury to the person in mounting the seat member 15. Preferably, the outer surface of the padded gripping portion or hand hold 16 is roughened somewhat, as by knurling or longitudinal corrugations, although, in some cases, the surface may be relatively smooth, particularly when the member comprises a section of ordinary rubber garden hose or similar tubing.

The swing, as thus far described, constitutes the inventive subject matter retained in the parent application, Serial No. 566,185, hereinbefore noted and from which the present invention is divided, and enters directly 90 into the present invention only insofar as it cooperates with the taking off platform device or the like, to be now described.

Obviously, in some cases, particularly in which the jump or take off is at all times from one and the same location, any conveniently arranged and located raised support or platform will suffice, but, in accordance with the present invention and the carrying into effect of one of its principal 100 objects and advantages, it is preferable to provide a supporting frame or stand with an arcuate series of steps, landings, or platforms, at different elevations but all within the same range with respect to the swing, that is, they are substantially equidistant 105 from the swing pivot, whereby the user may grasp the hand hold 16 in the same manner at whatever elevation he may be standing on the taking off device and likewise jump 110

and mount the seat 15 of the swing from whatever elevation he may desire to take off. As shown in the drawing, for a particular adaptation of the invention, the taking off device comprises a pair of arcuate side frame members 17, preferably formed of a single metal bar or rod looped at its middle to afford an intermediate guard portion 18 at the top of the device, the lower end portions of said side members 17 being turned downwardly, as at 19, to afford supporting feet for the lower inner portion of the frame.

At intervals the arcuate side frame members 17 have pivotally attached thereto, as at 20, step members or platforms 21, any desired number of which latter may be provided according to the size of the device and the swing with which it is to be used. As shown, there are five of these step members or platforms 21, and they are hingedly attached at their ends, as at 22, to arcuate connecting and supporting bars or rods 23. At opposite points above the topmost step member or platform 21 the side frame members 17 have pivoted thereto, as at 24, the angular upper end portions 25 of side members 26 of a foldable supporting frame comprising said members 26 and the crossed brace members 27 (see Fig. 2 of the drawing). The upper end portions of the arcuate connecting and supporting bars or rods 23 are also hingedly attached, as at 28, to the angular end portions 25 of said foldable supporting frame members 26.

The curvature of the arcuate side frame members 17 of the taking off device is on a radius from the pivotal supporting axis of the swing element 9, and the device is set with respect to the swing so that there is ample clearance between the seat member 15 of the swing and the inner edges of the step members or platforms 21. For example, in an apparatus of a certain size the pivotal supporting axis of the swing element 9 may be ten feet above the ground or floor and the seat member 15 at or about one foot above the ground or floor when the swing element 9 is directly vertical, as illustrated in full lines in Fig. 1 of the drawing, and the inner edge portions of the step members or platforms 21 of the taking off device are in an imaginary arcuate line approximately ten inches from the bottom of the swing member 15 in its sweep at full tautened length of the swing element 9, as illustrated by the dotted lines in Fig. 1 of the drawing. So, too, when the swing element 9 is kinked and held tautened between the bend and the pivotal axis of the element, as in the further illustration by dotted lines in Fig. 1 of the drawing, which is the condition of the swing element when grasped by the user when standing on one of the step members or platforms 21 of the taking off device, the mar-

ginal portion of the seat member 15 travels along the same imaginary line as the bottom of the seat, as before described. By this arcuate arrangement of the series of step members or platforms 21 of the taking off device it is obvious that said device may be adjusted with respect to the swing element 9, so as to increase and decrease the clearance between the seat member 15 and the inner edge portions of the step members 21, at will, and the clearance between each and every one of the step members or platforms 21 and the arcuate line of sweep of the seat member 15 will be uniform, or substantially so, at whatever clearance for which the device is adjusted, and the adjustment is obviously effected by merely moving the taking off device in a horizontal or a vertical plane only.

That is to say, in some cases, the taking off device will be merely moved along the ground or floor with respect to the truly vertical pendent position of the swing element 9, while, in other cases, the device may be raised and lowered bodily without shifting it from its vertical plane. It is also obvious that provision may be made for moving the device radially toward and from the pivotal supporting axis of the swing element 9. However, it is the broad idea of the provision for equal clearance between the different step members or platforms of the device and the swing seat 15, together with the broad idea of provision for adjustment to vary the clearance and still maintain substantial uniformity in the same with respect to the several step members or platforms 21, which concerns the present invention, and, the particular method of effecting the adjustment being obvious as described, it is deemed unnecessary to illustrate details of any particular means of adjustment.

In using the apparatus the user mounts the taking off device while holding onto the swing and leaps from one of the step members or platforms 21 thereof, supporting himself bodily after leaping by his grasp upon the suspension element 9 of the swing, and while so holding onto the swing throws himself upon the seat astride the lower part of the grasping portion 16. The peculiarly inclined and preferably arcuate arrangement of the series of step members or platforms 21 is of special advantage in cooperation with the swing, particularly a swing of the single suspension type with the circular disc-like seat as shown, in that the take off may be made with the same facility from the elevation of any one of the step members or platforms and the user receives the benefit of the exhilarating physical exercise as well as the pleasure of swinging, with muscular relaxation after his body has settled supportingly on the seat member 15. In addition to the muscular exertion in leaping from the taking off device and easing his body

upon the swing seat member 15, the user may derive further beneficial exercise by changing his posture after settling himself upon the seat member 15, and also from the exercise occasioned in mounting the steps of the taking off device. Hence, from the foregoing it will be seen that the device is equally efficient for the pleasure and benefit of adults as well as children and, obviously, may be accordingly made in various sizes depending upon the particular use of the apparatus and the place where it is to be located, either indoors or outdoors.

The taking off device illustrated in the accompanying drawing is, of course, foldable, but it is obvious that the device may be made non-foldable and of wood or other material instead of metal, or from a combination of materials and changed structurally in many particulars without in the least departing from the spirit and scope of the invention as defined by the appended claims. The invention, therefore, is not limited to the specific construction and arrangement shown.

Having thus described my invention, what I claim as new and desire to secure by Letters Patent is:

1. The combination of a swing, and a taking off device in cooperative relation to said swing, said taking off device having a series of separate platforms at different elevations in stepped relation to each other and substantially equidistant from the pivot of the swing.

2. The combination of a swing, and a cooperative taking off device comprising an arcuate series of separate platforms at different elevations and in stepped relation to each other, said platforms being substantially equidistant from the pivot of and having the same range of clearance with respect to the said swing.

3. The combination of a single suspension swing having a straddle seat at its lower end, and a cooperatively associated taking off device comprising a series of superposed steps within substantially the same radius from the pivot of said swing and with equal clearance between them and the seat in the arcuate sweep of the latter.

4. The combination of a single suspension swing having a straddle seat at its lower end, and a cooperatively associated device comprising an inclinedly arranged series of superposed steps substantially equidistant from the pivot of said swing whereby to be mounted by the user in reaching distance of the swing from any step.

5. The combination of a swing, and a cooperatively associated taking off device comprising a series of inclinedly and arcuately arranged superposed steps substantially equidistant from the pivot of the swing.

6. The combination of a swing, and a co-

operatively associated taking off device, said swing and taking off device being relatively adjustable in working relation to each other, said taking off device comprising an arcuate stepped series of platforms substantially equidistant from the swing pivot.

7. In an apparatus of the character described, a supporting frame, a swing comprising a single suspension flexible element supported at its upper end on said supporting frame for universal swinging movement, a disc-like seat centrally supported at the lower end of said flexible swing element, the lower portion of said swing element in the region of said seat being covered with padding material affording a hand grip and a cushion for that part of the user's body contacting therewith, and a portable taking off device cooperable adjustably with respect to said supporting frame in working range of said swing, said device comprising an inclined arcuate series of superposed steps equidistant from the swing pivot.

8. The combination of a swing, and a cooperatively associated portable and collapsible taking off device comprising an inclined series of foldably supported platforms arranged in stepped superposed relation, the forward marginal portions of said platforms being coincident with an arcuate line on a radius from the swing pivot whereby the several steps are mountable by the user with equal reaching distance of the swing.

9. In an apparatus of the character described, a supporting frame, a single suspension swing element universally swingably supported from said frame, a straddle seat at the lower end of said swing element, the lower portion of said swing element in the region of said seat being constructed to afford a hand grip, and a taking off device cooperatively associated with said supporting frame and comprising a stepped series of platforms with their forward edge portions coincident with an arcuate line on a radius from the swing pivot whereby the swing is in equal reaching distance of the user from any one of the platforms.

10. In an apparatus of the character described, a supporting frame, a single suspension swing element universally swingably supported from said frame, a straddle seat at the lower end of said swing element, the lower portion of said swing element in the region of said seat being constructed to afford a hand grip, and a portable taking off device positionable adjustably in cooperative relation to said supporting frame, said device comprising an arcuately arranged stepped series of superposed platforms, the forward edges of said platforms being equidistant from the swing pivot.
